(57) **CLAIM**

The ornamental design for a bottle as shown and described.

DESCRIPTION

FIG. 1 is a first perspective view of a bottle.

FIG. 2 is a second perspective view of the bottle shown in FIG. 1.

FIG. 3 is a front view of the bottle shown in FIG. 1.

FIG. 4 is a back view of the bottle shown in FIG. 1.

FIG. 5 is a left view of the bottle shown in FIG. 1.

FIG. 6 is a right view of the bottle shown in FIG. 1.

FIG. 7 is a top view of the bottle shown in FIG. 1.

FIG. 8 is a bottom view of the bottle shown in FIG. 1.

FIG. 9 is a first exploded perspective view of the bottle shown in FIG. 1; and,

FIG. 10 is a second exploded perspective view of the bottle shown in FIG. 1.

The broken lines shown in the drawings are included for purposes of illustrating portions of the bottle and form no part of the claimed design.

1 Claim, 9 Drawing Sheets
